PROCESS FOR OBTAINING MULTICOLOR PICTURES

Pierre Danlos, Neuilly-sur-Seine, France

Application January 9, 1945, Serial No. 571,972
In France December 20, 1943Section 1, Public Law 690, August 8, 1946
Patent expires December 20, 1963

4 Claims. (Cl. 95—2)

1

This invention relates to the color-photography and particularly to the production of films in two, three or four colors, from photographic films carrying different photographic silver halide images, which are to be found, either on the same level, or on different levels, in a single coating, or alternatively in superposed different coatings, on the same side, or on both sides of a transparent support, said pictures being obtained by the well known process, which comprises printing with positives, developing and removing the negative silver images to obtain a composite positive silver halide image still sensitive to light action.

The principal object of the invention consists of a process, particularly characterized by the fact that the various silver halide images considered are differentiated by an optical method, according to which said film is to be submitted to one or more successive differential exposures, by means of actinic excitations that may vary from one point to another, in such a manner that, during each exposure, one of the images included in the film is wholly exposed to the effect of light, while the others remain quite unaltered by said effect, said film being submitted, after each exposure, to a suitable treatment, the other images being subsequently, in their turn, submitted to a suitable treatment.

A particular embodiment of said process consists of a method according to which a differential isolation or exposure is obtained by means of a special element which shall be called "differentiating unit" and which may, for instance, be made up by superposition on one film or on a plurality of assembled different films, in suitable register, of a negative of the image which is to be exposed and of the positives of the images which are not to be exposed. Each point of the composite sensitive image is exposed through the corresponding point of the differentiating unit so that the action of actinic light will be, on each point, proportionate both to the illumination impressed and local density.

If said film comprises several images to be differentiated, either on the same side, or on both sides of that film, several "differentiating units" will be used, each of which corresponds to the image to be differentiated and constituted as above explained, said "units" being utilized successively.

The invention relates equally to the different particular treatments to which said film has to be submitted, after each exposure, by means of a "differentiating unit," or by any other means, said treatments being different according to the

2

number of images and of colors which are to be obtained. Those treatments will be pointed out by the help of the explanations given hereinafter in the present specification with respect to the most particular important cases which may occur practically.

Finally this invention comprises not only the optical differentiation process mentioned above, and its method of realisation by means of said "differentiating units," but also, on the one hand, said "differentiating units" constituted as it has been pointed out above and, on the other hand, the colored films designed, for instance, for motion pictures and obtained by application of said process.

The characteristic feature of the process according to the invention, that is, the differential exposure of a composite sensitive image, offers the advantage over the known differentiation processes which operate either in a chemical way, or in a mechanochemical way, that it renders it possible the use of common single silver halide emulsion films in which the various images to be differentiated lie on any level, even, on the same level in the emulsion itself, which was impossible with said known process, the latter being applicable only if said images lie on different levels. With those former processes it was necessary, in order to prevent the images from being on the same level, to take particular and expensive precautions or to use inevitably a film provided with several emulsions on the same side of the support. According to this invention, on the contrary, no such necessity exists, though the new process enables a film coated with a plurality of emulsions to be utilized.

The invention and its applications will be more easily understood by the help of the following specification.

40 The accompanying drawing, which relates to a particular example, illustrates diagrammatically the conditions of the problem to be solved and the manner in which the solution thereof may be found by means of the "differentiating unit."

45 The invention is based on the following observation: When a single silver halide emulsion is exposed to light through a positive, developed, and the silver removed, under inactinic light, by means of a process utilizing bichromate or acid

50 potash permanganate, for instance, the silver halide image thus formed is still sensitive to light and its sensitivity, at any point, is a function of the concentration of the sensitive silver halide grains remaining at the same point; the result is that such an image may be developed with a

complete gradation, from black to white, after a simple uniform exposure to light and without the help of a negative. It may be verified that, in that case, a uniform action of light may produce practically the same effect as that which may be caused by different excitations at each point corresponding to printing through a negative. Everything considered, it was easy to foresee such a result, since the concentration of grains still sensitive to light, in whatever point of the image in question, is a function of the brightness of the original subject in that point. In the following considerations, the denominations "brightness of the subject" or "concentration of sensitive grains" will be used indifferently in order to point out the sensitivity of the sensitive image, in whatever point of the subject.

Let us consider now a sensitive image obtained in such conditions, said image being exposed to light, that is, isolated, with a sufficient luminosity; we may then observe that it will be possible to carry out the development until such a point that the sensitive image be separated in two images, practically identical, the former of said images being constituted by reduced silver and the latter by a silver halide which remains still sensitive to light.

The sensitive image, thus separated, may still be considered as the aggregate of two half-images, the one being identical to the other. It will then be seen that two identical images, situated on the same level of a single emulsion, have thus been separated or differentiated by that process.

We have now to consider what occurs generally when, instead of two identical images, we have two different images, which is the case with images proceeding from different color sensations of the same subject. We may observe immediately that a uniform exposure is not able to cause satisfactory results, since the two primitive images are not identical. Consequently it is necessary to differentially expose the sensitive images, that is produce actinic excitations that may vary from one point to another and, for this purpose, we shall utilize a particular element, namely "the differentiating unit" and the object of the considerations hereinafter developed is to specify the conditions to be fulfilled by said unit in order to obtain a total exposure for one of the part images without acting, in any way, on the other. For instance, in order to fix the ideas on this matter, the case of a bichrome or two-color film will be considered; the images to be differentiated being called respectively A and B, and I the primitive image which is the sum of said images A and B. Moreover, it will be supposed that the former (image A) is to be differentiated in a state of reduced silver, while the latter (image B) remains in a state of silver halide, still sensitive to light.

It will be ascertained immediately that the density at any point of said image I is equal to the sum of the respective densities of the two images A and B at the same point. Taking that remark into consideration, as well as the above enunciated fact, namely that a uniform action of light on the image I involves the same effect as a variable action produced by means of a negative on an ordinary emulsion (not an image form), it may be easily concluded therefrom that the transparencies of the "differentiating unit," at any given point, must be proportionate to the ratio A/B of the sensitivities of images A and B at the corresponding point, not taking into consideration the absolute values of the sensitivities of said images A and B at the same point.

More particularly and in order to give an example, if several points m, n, o, p, . . . and so on . . . of said image I present certain relations of brightness A/B, equal to each other, such as 5 $Am/Bm=An/Bn=Ao/Bo=Ap/Bp$, and so on . . . the transparency of the "differentiating unit" shall be the same for these various points, whatever the absolute value of the sensitiveness of said image I may be, in other respects, at the points m, n, o, p, and so on . . . that is to say even if these points are comprised in very different parts of the subject I, such as very dark parts or light tones.

Moreover, if the quotient A/B becomes very great at any point, it means that B is almost equal to zero at that point; consequently the transparency of the "differentiating unit" must become very great in order to permit a total insulation to be applied to image A at the point in question. On the contrary, if the quotient A/B becomes very small at any point, it means that A becomes almost equal to zero, from which it results that the transparency of the "differentiating unit" at that point must be as low as possible, in order to prevent any action of light on the image B at the point in question.

Consequently the invention, according to which a solution has been found to the above enunciated problem, consists in submitting the film carrying the images A and B to the effect of light, by means of a particular element, such as the "differentiating unit" mentioned above, or otherwise, in order to obtain the whole exposure of one of said images, while the other remains unexposed.

35 Said "differentiating unit" in the case of two images A and B may be formed by the superposition of the negative of the image A which is to be exposed and of the positive of the other image B which is not to be exposed, said positive and 40 negative being optionally included in the same film or in two separated films joined carefully in register.

Moreover, the following conditions must be fulfilled as exactly as possible:

45 A. The negatives A and B must be submitted to light action in such a manner that, if there is a gradation of gray-neutral tints said gradation is to be printed identically on the negative A and on the negative B;

50 B. The positive printed from negative B is to be developed to $\gamma=1$, and submitted to light action in such a manner that its mean density will be equal to the mean density of the negative B, which may be verified by superposing the positive B on the negative from which it proceeds.

55 As a consequence of that operation, the image observed by transparency should show the same transparency on its whole surface. Such a result is rigorously possible only if all the previous operations have been carried out very carefully, as well for the negatives as for the positives, in order to register the luminous elements of the original subject, only on the straight part of the representative curve of each emulsion utilized. 60 Since that operation is subject to frequent and easy causes of errors, that condition when it is fulfilled, affords a practical method of controlling the quality of negatives, which offers a real interest for the operator.

65 Thanks to the annexed drawing, which relates to the case of a two-color film, it is easy to understand the problem enunciated and the conditions in which the "differentiating unit" operates.

70 Image I, included in the film, is supposed to be 75 an aggregate of two images of different colors A

and B. The columns 1 and 2 of the drawing illustrate respectively the negative NA of the image A and the positive PB of the image B, the sum of which forms the "differentiating unit" M. Columns 3 and 4 illustrate diagrammatically the image I, resulting from the combination (or sum) of the sensitive images A and B.

It has been assumed, for the clearness of the description, that the sensitive images A and B are situated in two superimposed emulsions. Vertically, in said columns, interval $a-b$ represents the wedge, or scale of chiaroscuro, printed in A and in B, with the same exposure. The interval $c-c'-e$ represents two wedges, the one situated in A being put in a certain direction and the other situated in B in the reverse direction, which gives the possibility of obtaining every possible value of the quotient A/B. In the column 5, the flux L irradiated from the light source has been represented. The most intense density of the negative NA is denoted by d , said density being, as usual in the photographic technology, indicated in the system of the decimal logarithms (where d is the logarithm of opacity) and assumed to be equal to that of the positive PB. In the column 6, the quantities of light transmitted by the "differentiating unit" have been registered and finally the column 7 gives the value of quotient A/B.

It has been ascertained that, in the interval $a-b$, as explained above, the quotient A/B remains unchanged and equal to unity and, equally, that in the same interval $a-b$, the superposition of the corresponding elements having the same value in the negative NA and in the positive PB, gives really an area the density of which is uniform and equal to d , as required.

In the interval $c-e$, the quotient A/B varies between zero and the infinity and it may be pointed out that, in c' , namely in the middle of said interval $c-e$, it becomes equal to unity, which involves, for the density of the "differentiating unit" at the corresponding point, the value d . At the point c , where the quotient A/B is almost equal to zero, the density of the "differentiating unit" will reach its maximum, which prevents image B from being exposed, while in e where the quotient A/B approaches infinity, the density of said "differentiating unit" will be nil, thus enabling the whole of the light to exert its action on the image A. Let us call l the flux (expressed in lux) capable of printing entirely the part $a-b$ of image A, we shall verify that, starting from an incident flux $L=1 \times 10^d$ where d represents the density, only a flux $L'=1/10^d$ will be transmitted at point c , while at point e , the totality of the flux $L=1 \times 10^d$ will be transmitted.

Therefore it appears clearly that, if on the one hand, it may be possible to reduce the quotient $1/10^d$ sufficiently in order not to print the image B, at all, where its sensitivity is maximum, and, on the other hand, to obtain a value of 1×10^d large enough to expose completely image A at its maximum of sensitivity also, the problem will be entirely solved.

Moreover, l being a constant quantity which depends on the absolute sensitiveness of image I, it is easy to see that d is the variable quantity of the system, $2d$ representing the maximum of density, and that consequently there is a minimum value of d , above which said problem always admits a solution.

Practically, instead of taking separately the original negative of image A and a positive printed to $\gamma=1$ of image B, it is preferable to print an intermediate positive of said image A,

which is developed also to $\gamma=1$ with the precautions indicated above. The "differentiating unit" is then printed by utilizing as a compound negative:

5. 1. The original negative of said image B, and
2. The intermediate positive printed through the negative A, said negative and positive being accurately superimposed in register in the printing machine, between the light source and the matrix film.
10. With that method it is possible not only to avoid the obligation to use two separate matrix-films for mass production positive printing but also to obtain, on the "differentiating unit" different degrees of density d which depend only on the time of exposure and on the gamma chosen for developing and are independent of the degree of density of the original negatives.
15. The film, after exposure by means of the "differentiating unit" for instance, is submitted to various treatments according to its constitution, according to the number of images which it carries and finally according to the colors which are to be given to the different images, for instance, blue-green, magenta, yellow.
20. After developing and coloring the first exposed image, the other images are submitted to daylight and developed and treated then in their turn, in order to obtain the colors required, or, according to circumstances, if it is necessary, another image is exposed to the action of light through another "differentiating unit" comprising the negative corresponding to that image and the positives corresponding to the remaining images, the second image, thus exposed, being developed and suitably treated and then the other remaining images are exposed to the daylight, developed and treated; those successive operations may be repeated several times.
25. Practically, if there are several images to be differentiated, several "differentiating units" are used, the constitution of which corresponds respectively to each of said images and after each insolation, the image which has just been exposed, is developed and suitably treated in a convenient manner, the remaining images being then submitted to a suitable treatment.
30. The successive differentiation of several images included in a sole emulsion, by an exposure in which light acts on the same side of the support, may require certain precautions in order to prevent the image already differentiated and developed constituting, up to a point, an obstacle for the following operations. In that case, it is advantageous to transform the image already developed, before the following insolation, into a colored element the absorption spectrum of which assures the passage of actinic rays.
35. The following examples, limiting by no means the scope of the invention, and by the help of which some practical applications of said invention are examined, point out different processes which may be applied.
40. I. Realisation of a two-color or bichrome-film on an ordinary film coated with a single silver halide emulsion.
45. After printing, through part positives, of the images A and B, and developing and removing the negative silver images, the film is dried and differentially exposed through the "differentiating unit" defined above; said film is then developed in a developer of usual type as, for instance, a hydroquinone developer. Said film must then be treated, either by mordanting and, afterwards, by toning, or by a process able to develop directly

50. 60. 65. 70. 75.

After printing, through part positives, of the images A and B, and developing and removing the negative silver images, the film is dried and differentially exposed through the "differentiating unit" defined above; said film is then developed in a developer of usual type as, for instance, a hydroquinone developer. Said film must then be treated, either by mordanting and, afterwards, by toning, or by a process able to develop directly

the colors by means of a color developer such as of the diethyl-paraphenylenediamine type.

In the first case, the film in which the images A and B have been differentiated, as described above, is washed and treated with a solution of potassium iodide which transforms the silver halide constituting the image B into iodide of silver, without practically acting on the deposit of reduced silver which constitutes the image A.

The image B is then dyed by immersing the film in a solution of safranine and auramine, containing a suitable quantity of acetic acid, the excess of coloring matter is carried away by washing, then silver iodide is eliminated in a hypo fixing bath, after having taken care to fix the coloring matter on the gelatine of the emulsion by the help of a tanning bath. It remains then to tone image A in blue-green, which is done by immersing said image in a ferric toning bath. The ferrocyanide of silver formed in the toning bath is then eliminated and, afterwards, the film must be washed and dried.

In the second case, the film in which the images A and B have been differentiated is bleached, under an inactinic lighting, in order to transform image A into silver chloride and said images are then developed in a special developer, such as the diethyl-paraphenylenediamine developer, for instance, with the addition of a suitable coupling agent, in order to obtain the color of image A. The film is then exposed to daylight and image B is directly developed in a bath of the same type the coupling element of which corresponds to the color of said image B. It remains then to eliminate reduced silver from images A and B, which is effected by immersion in Farmer's liquor, and finally the film is washed and dried.

II. Production of three-color pictures on a film coated with a silver halide emulsion on each side.

In this case there are three elementary images: A, B and C, A and B being situated in the same emulsion coating, while C lies on the other side of the support. The images A and B are differentiated as described above; image A appears in the state of reduced silver, while B, as well as C on the other side of the support, remain in the state of silver halide. The images B and C may then be treated by mordanting and dyed separately magenta and yellow, while A will be treated by the ferrocyanide toning bath, as described with regard to the bichrome process. It is possible also, under inactinic lighting, to convert the image A into silver chloride and to develop said image again, always under an inactinic lighting, in a bath containing one diamine and a coupling agent in order to obtain the blue-green image. After bright exposure, images B and C will be developed, with the corresponding coupling agents, in such a manner as the colors magenta and yellow will appear directly in said images on both sides of the support. Reduced silver must be eliminated as above described.

III. In the case of a system including four colors, the images A and B, the sum of which forms image I on one side of the support, and the images A' and B', the sum of which forms image I' on the other side of the same support, must be differentiated, said differentiation being carried out, of course, by means of two "differential units," instead of a single one.

For instance the images B and B' will be treated by mordanting and dyeing while images A and A' will be treated by toning.

It is also possible, by application of a similar process, to treat the four images separately by

means of a diethyl-paraphenylenediamine developing bath the oxidation product of which acts upon the coupling element, phenol or naphthol forming thus an insoluble coloring element, which is generally some such body as the indamine or the indophenol.

IV. Finally the case of a three-color film may be contemplated, said trichrome film being obtained with an ordinary single silver halide emulsion coated film. In that case, the totality of the colored sensations preceding from the subject are registered by means of part positives in the single emulsion and the composite positive silver halide image is obtained by developing and removing the silver negative image. After the film has been dried under inactinic lighting, the image A corresponding to the blue-green sensation is exposed, for instance, by means of a "differentiating unit" which comprises not only negative A and positive B, but also positive C.

Exposure is carried out on the emulsion side and the time of said exposure, as well as the following development, are controlled in order to reduce into the state of metallic silver about one third of the total amount of silver salt corresponding to gray neutral tints; still under inactinic lighting, the image A is then converted into chloride in order to develop it again with a developer producing the blue-green coloring element and then we are again before the same problem the object of which is the differentiation of two images B and C, the former (image B) corresponding to the sensation of the magenta color proceeding from the subject and the latter (image C) to the sensation of the yellow color.

A second "differentiating unit" is then used, said matrix being obtained as described above in the case of a two-color film, and the film is exposed to the action of light on the side of the support of said image. Then development is carried out in an alkaline pyrogallol developing bath, alkalisation being obtained by addition of caustic soda, in the presence of a small quantity of sodium sulphite, or even without sodium sulphite; the yellow coloring element is thus formed. In that case, development must still be controlled so that about one third of the total amount of silver halide constituting the gray neutral tints will be reduced. The film is brightly exposed and developed in a different bath which produces the magenta coloring element. Reduced silver is then removed by the help of Farmer's liquor and finally the film is washed and dried.

Various modifications of the several specific illustrations given by way of example herein will occur to those skilled in the art and it is intended that the invention herein described be interpreted as broadly as defined in the claims.

I claim:

1. Process for obtaining a three color picture on a support coated with a single silver halide emulsion, which process comprises: printing into said emulsion in registered superposition with three positive part pictures in such manner as to produce a composite negative image representing the three positive part pictures, developing and removing the negative silver image in order to obtain a composite positive silver halide image sensitive to light; differentially exposing the said sensitive image while in register with a differentiating unit formed by the superimposition of the negative of the first component picture to be exposed and of the two positives of the second and third component pictures not to be exposed, developing and transforming the said first compo-

ment picture into its elementary colored picture; differentially exposing the said film again while in register with a second differentiating unit formed by the superimposition of the negative of the second component picture to be exposed and of the positive of the third component picture not to be exposed, developing the said second component picture and transforming both second and third component pictures, each into its elementary colored picture, respectively.

2. Process for obtaining three color picture on a support bearing a silver halide coating on each side of the support, which process comprises: printing in register into the coating on the first side with first and second positive part pictures in such manner as to produce a composite negative image representing said first and second positive part pictures, and registering into the coating on the other side the third positive part picture, developing and removing the negative silver images in order to obtain on the first side a composite positive silver halide image sensitive to light; differentially exposing the said composite sensitive image while in register with a differentiating unit formed by the superimposition of the negative of the first component picture and of the positive of the second component picture, developing and transforming the said first component picture into its elementary colored picture, transforming both second and third component pictures each into its elementary colored picture respectively.

3. Process for obtaining a three color picture on a support bearing a silver halide coating on each side of the support, which process comprises: printing in register into the coating on the first side with first and second positive part pictures in such manner as to produce a composite negative image representing said first and second positive part pictures, and registering into the coating on the other side the third positive part picture, developing and removing the negative silver images

in order to obtain on the first side a composite positive silver halide image sensitive to light; differentially exposing the said composite sensitive image while in register with a differentiating unit formed by the superimposition of the negative of the first component picture and of the positive of the second component picture, developing the said first component picture, transforming both second and third component pictures each into its elementary colored picture respectively, finally turning the first component picture into its elementary colored picture.

4. In a process for obtaining a multicolor picture on a support coated with at least one silver halide emulsion, the steps of printing into said emulsion in registered superposition with a plurality of positive part pictures in such manner as to produce a composite negative image representing said plurality of positive part pictures, developing and removing the negative silver image in order to obtain a composite positive silver halide image sensitive to light, differentially exposing the said sensitive image while in register with a differentiating unit formed by the superimposition of the negative of the first component picture to be exposed and of the positives of the remaining of said plurality of component pictures, not to be exposed, and developing and transforming the said first component picture into its elementary colored picture.
